UNITED STATES PATENT OFFICE.

EVERTON S. WALRATH, OF ANNAPOLIS, MARYLAND.

BIT.

Application filed July 2, 1924. Serial No. 723,779.

This invention relates to wood-boring tools and is intended more particularly for the use of plumbers and steam fitters in forming the openings through floors for the passage of pipes. It is now the general practice to form such openings at a single operation by the use of expansion bits which comprise a boring drill and a radially disposed cutter bar carried by the shank of the drill and projecting laterally therefrom so that the drill bores an initial opening and the cutter bar enlarges or expands the opening by cutting away the wood immediately surrounding the initial opening. This operation is very laborious and frequently causes chipping of the wood because the cutting proceeds very slowly and the cutter bar fails to engage the wood evenly so as to work steadily. It is, therefore, the object of my invention to provide a simple and inexpensive tool whereby the required opening may be expeditiously formed with minimum labor and the completed opening will be clean and free from splintered walls. One embodiment of my invention is illustrated in the accompanying drawing and will be hereinafter fully set forth, the novel features being particularly pointed out in the appended claims.

30 In the drawing:

Figure 1 is a side elevation of my improved tool showing the same applied at a point where an opening is to be formed;

Fig. 2 is a diametrical section of the working part of the tool;

Fig. 3 is an elevation taken at a right angle to Fig. 1 with the cutter bar in section on the line 3—3 of Fig. 2;

Fig. 4 is a detail section of the cutter on the line 4—4 of Fig. 2, and

Fig. 5 is an elevation showing a slight modification.

The tool embodying my invention comprises a shank 1 constructed at its upper end with a tapered angular portion 2 adapted to fit within and be secured in the socket of an ordinary brace. The opposite end of the shank is preferably expanded and formed into a substantially cylindrical head 3, the lower portion of which is exteriorly threaded, as shown at 4. Upon one diameter of the head 3 an opening 5 is formed therethrough and the wall of said opening is preferably inclined, as shown clearly in Fig.

2. Upon the axis of the head 3, an opening 5 is formed extending from the diametrical passage 5 to the lower extremity of the head and within this opening or bore 6 is engaged a set screw or bolt 7. The cutter bar comprises a cylindrical stock or base member 8 of a diameter slightly less than the diameter of the opening 5 so that it may be easily inserted in said opening, and this base member or stock has its circumferential surface disposed angularly with respect to its ends so that it will conform to the inclination of the wall of the opening 5, one side of the cylindrical stock being flat for engagement with the set screw so as to prevent rotation of the cutter within the bore 6, as best shown in Fig. 3 of the drawing. From the base portion 8, the cutter extends laterally in the form of a bar 9 having its upper surface beveled downwardly and forwardly, as shown at 10, whereby to meet its under surface 11 in a sharp cutting edge 12. It will be readily noted that the bar 9 is slightly inclined so that the outer extremity of its cutting edge 12 will engage the floor 13 before the inner end thereof engages the latter and the engagement of the cutting edge with the floor will proceed progressively from the outer extremity of the same to the inner end thereof to produce a shearing cut which will minimize the strain upon the tool and lessen the labor needed to turn it. It will also be noted more particularly upon reference to Fig. 4 that the under side 11 of the bar is inclined slightly upwardly and rearwardly so that clearance is provided between the said surface and the surface of the floor in rear of the cutting edge and frictional resistance to the turning of the tool is thereby minimized. At the extreme outer end of the cutter bar is a depending tooth 14 which is sharpened so that it will readily penetrate the floor and easily cut through the same as the tool is rotated.

In boring through a floor or other wooden member to provide an opening in which a steam, water or other pipe may be fitted, the workman will take the ordinary straight boring drill or auger and cut a circular opening through the floor of the same diameter as the head 3 of my tool. The auger is then withdrawn and my tool substituted therefore in the brace. The end of the head 3 is then inserted in the opening, indicated

at 15, and the tool rotated, the threads 4 biting into the wall of the opening 15 and serving to maintain the axis of the tool alined with the axis of the opening and also serving to feed the tool through the opening as it is rotated. The labor of turning the tool and forming the finished hole is thus very materially reduced. The tool may be rotated somewhat rapidly until the cutting 10 tooth 14 meets the surface of the floor when, of course, it will be rotated more slowly in order that the tooth may penetrate the floor and cut through the same to define a circle having the same diameter as that desired for 15 the finished opening. The tool will be fed constantly forward as it is rotated and eventually the cutting edge 12 will be brought into contact with the surface of the floor and will begin to shave therefrom a portion of 20 the wood between the tooth 14 and the opening 15. The cutting away of the wood will thus be performed progressively and, therefore, the tendency of the wood to chip and splinter at the wall of the opening is over- 25 come and a clean cut opening is produced quickly and with a minimum expenditure of labor.

The set screw or bolt 7, of course, binds the base member 8 of the cutter within the 30 opening 5 of the tool head, and the inclination of this base member together with the inclination of the wall of the opening 5 in which the said member is received will effect a wedging action of the base against the end 35 of the set bolt or screw under the resistance encountered by the cutter when the tool is operated. Within the limits of the length of the base member 8, the cutter may be ad- 40 justed radially so that openings of different diameters may be formed, and this capability of the device to produce openings of various diameters may be increased by pro- 45 viding a plurality of interchangeable cutters of different lengths. The inclination of the opening 5 through the head 3 also facilitates the clearance of shavings and sawdust there- from.

In Fig. 5 I have shown a longitudinal groove 16 formed exteriorly in the threaded 50 extremity 4 of the head 3, thereby reducing the weight of the device and also reducing the extent of surface which creates frictional resistance between the head and the bore of the opening 15, so as to facilitate rotation of 55 the tool. It is to be particularly noted that the set screw or bolt by which the cutter is secured in the head is disposed at the lower extremity of the head along the axis of the same so that it offers no resistance to the insertion of the tool in the previously formed 60 opening in the floor nor to the progress of the tool after it is inserted. Moreover, by this arrangement I avoid extensive mutilation of the threads 4 and also eliminate pro- 65 jections or other surfaces which would tend

to gouge the wall of the bore or opening 15 and thereby resist the operation of the tool and subject the same to jerks and stops which tend to cause chipping and splintering of the wall of the completed opening. 70 The tool is exceedingly simple and may be produced at a very low cost.

Having thus described the invention, I claim:

1. A boring and reaming tool comprising 75 a substantially cylindrical head having its lower portion exteriorly threaded and adapted to be inserted in a previously formed opening, said head having a transverse opening therethrough piercing the threads and 80 having its lower end flat and smooth and provided with an axial bore communicating with said transverse opening, a cutter bar having a cylindrical stock fitted within the opening and provided with a flat surface, 85 and a set screw threaded in the bore and having its outer end provided with a tool-engaging head and its inner end adapted to clamp the cylindrical stock at the flat surface 90 thereof.

2. A boring and reaming tool comprising 95 a substantially cylindrical head having its lower portion exteriorly threaded and adapted to be inserted in a previously formed opening, said head having a downwardly inclined transverse opening therethrough 100 piercing the threads and having its lower end straight and flat and pierced by an axial bore communicating with said transverse opening, a cutter bar fitting within the trans- 105 verse opening and including a cylindrical stock having its circumferential surface dis- posed angularly with respect to its ends to conform to the inclination of the wall of the transverse opening, said cylindrical stock being provided with a flat surface, and a set screw threaded in the walls of the axial bore and adapted to engage the flat surface of the cylindrical stock of the cutter, the outer end 110 of the set screw being provided with a tool- engaging head normally spaced from the flat lower end of the cylindrical head.

3. A boring bit comprising a substantially cylindrical head having its lower portion formed with threads whereby to provide for 115 feeding of the head through an opening in the work in the rotation of the bit, the said threaded portion of the head having a diametric cylindrical opening formed therein and inclined downwardly toward one side of 120 the head, a cutter bar having a substantially cylindrical stock fitted in said opening and having a flat underside, and a set screw threaded axially into the lower end of the head and binding at its upper end against 125 the flat under side of the said stock and securing the same in a definite fixed position within the opening, the cutter bar extending radially from the said side of the head and having its upper side beveled to meet the 130

plane of the under side of the bar and provide a cutting edge inclined downwardly on a continuous straight line to the outer end of the bar, the said under side of the bar being inclined upwardly and rearwardly from the said cutting edge of the bar and occupying a plane nonparallel to the flat

under side of the stock, the said bar being bodily inclined downwardly with relation to the head and being provided at its said outer end with a thin cutting blade depending from the under side of the bar. ¹⁰

In testimony whereof I affix my signature.
EVERTON S. WALRATH.
